UNITED STATES PATENT OFFICE.

JOHN H. BENSE AND JOHN WM. BENSE, OF OAKHARBOR, OHIO.

COMBUSTION-ENGINE.

No. 856,760.

Specification of Letters Patent.

Patented June 11, 1907.

Application filed July 18, 1906. Serial No. 326,726.

To all whom it may concern:

Be it known that we, JOHN H. BENSE and JOHN WM. BENSE, citizens of the United States, residing at Oakharbor, in the county of Ottawa and State of Ohio, have invented certain new and useful Improvements in Combustion-Engines; and we do hereby declare the following to be a full, clear, and exact description of the invention, such as will enable others skilled in the art to which it appertains to make and use the same.

Our invention relates to new and useful improvements in gas engines and more particularly to that class known as combustion engines and our object is to provide means for thoroughly mixing the gases employed as fuel with the air.

A further object is to provide suitable means for directing the fuel into the combustion chamber.

A still further object is to provide means for stopping the feed of the fuel and air into the combustion chamber when the engine has reached a certain speed.

Other objects and advantages will be hereinafter referred to and more particularly pointed out in the claims.

In the accompanying drawings which are made a part of this application, Figure 1 is a side elevation, partly in section, of our improved engine showing the position of the several parts when the piston is on its upward stroke the governor mechanism being omitted. Fig. 2 is a central sectional view through the engine and parts attached thereto showing the piston in its downward position and the fuel being directed into the combustion chamber, and, Fig. 3 is a detail plan view of a governor and valve controlling mechanism connected thereto.

Referring to the drawings in which similar reference numerals designate corresponding parts throughout the several views, 1 indicates the cylinder of our improved engine which is surrounded by the usual form of water jacket 2.

Disposed within the combustion chamber 3 of the cylinder 1 is a piston 4, said piston being provided with a closed head 5 at one end and open at its opposite end and is provided around its periphery near the closed end thereof with suitable packing rings 6. Pivotally connected within the piston 4 is a connecting rod 7, the lower end of said piston shaft being pivotally mounted upon a crank arm 8 which is rigidly secured to the driving

shaft 9, and the crank arm 8 is centrally disposed in a circular chamber 10 which is provided at its lower end with a suitable base 11 and by which means the cylinder 1 is supported.

The combustion chamber 3 is provided upon one side with an exhaust port 12 and upon its opposite side with an inlet port 13. The head 5 is provided at a point in line with the inlet port 13 with a deflector plate 14, the object of said plate being to direct the incoming fuel to the upper end of the combustion chamber as well as to prevent the exhaust from affecting the entrance of the fuel through the inlet port. Extending outwardly from the inlet port 13 is a mixing chamber 15 having a vertically disposed valve 16 at its outer end, said valve having a spring 17 surrounding the stem 18 of the valve thereby rendering the valve automatic in its operation. The valve 16 is adapted to engage a seat 19 provided in the upper end of a vertically disposed air tube 20 through which air is introduced into the mixing chamber 15 and it will be seen that when the valve 16 is closed that the air will be cut off from the mixing chamber.

Fuel such as gasoline or the like is disposed into the tank 21 and is directed through a pipe 22 which connects with a jet-tube 23 at the upper end of the air tube 20, the jet-tube being so located that when the valve 16 is resting upon its seat the inner end of the jet-tube will be closed thereby cutting off the fuel from the mixing chamber. To more readily regulate the flow of the fuel into the mixing chamber we have provided a needle valve 24 which is adapted to be directed into the jet-tube 23 to regulate the flow of the fuel therethrough and if desired the needle valve may be directed far enough inwardly to entirely close the jet-tube and stop the flow of fuel from the tank.

The chamber 10 is provided with an inlet pipe 25, the outer end of which is provided with a valve 26, the stem of the valve being provided with a suitable bearing 27 and having its extended end threaded to receive an adjusting nut 28, between which and the end of the bearing 27 is disposed a spring 29 by which means the valve 26 is held normally closed. By directing the nut inwardly or outwardly upon the threaded portion of the stem the tension upon the spring is increased or decreased.

By this construction it will be seen that

when the piston 4 is directed to the upper end of the combustion chamber 3 that a vacuum will be formed in the chamber 10 so that the tension of the spring 29 will be overcome and the valve 26 opened whereupon the chamber 10 will be filled with air. The upward movement of the piston 4 also relieves the pressure upon the lower side of the valve 16 whereupon the spring 17 will close the 10 valve and shut off the flow of fuel through the jet-tube 23. As soon, however, as the piston 4 starts on its return stroke the valve 26 will be closed and the air compressed in the chamber 10 and as soon as the upper 15 end of the piston has reached the inlet port 13 the compressed air in the chamber 10 will overcome the tension of the spring 17 and open the valve 16 thereby directing the air from the chamber 10 and fuel from the pipe 22 into the mixing chamber 15 where the 20 particles of fuel and air are thoroughly commingled before being discharged into the combustion chamber 3, the course of air and fuel being indicated by arrows in Fig. 2 of the drawing.

A governor 30 is employed in connection with our improved engine, said governor being operatively connected to the shaft 9 by means of a belt 31 or the like, so that when 25 the shaft 9 is rotated the governor will be operated. Each of the governor balls 32 is yieldingly secured to the upper end of the governor stem and caused to rotate therewith, each of said balls having a strap 33 secured to its lower edge and the lower end of said straps being yieldingly secured to a movable collar 34 which is slidably mounted upon the stem of the governor. When the 30 governor is rotated the momentum will move 40 the balls away from the stem of the governor and cause the collar 34 to raise on the governor stem. One end of a detent 35 is pivotally secured to the collar 34 while the opposite end thereof is disposed into co-operation with the stem of the valve 26, the detent 35 being provided with a pivot point 36 upon which the detent 35 is adapted to rock. The object in providing the detent 35 is to 45 control the speed of the engine it being understood that when the engine is traveling above a normal speed that the expansion of the governor will direct the free end of the detent into the path of the stem of the valve 26 so that when the valve is opened the 50 detent will be disposed in the path of the valve stem and hold the valve open, the result being that the air in the chamber 10 will be left free to pass out through the inlet pipe 25 thereby leaving the valve 16 closed and 55 the fuel cut off from the combustion chamber. As soon, however, as the engine has again attained its normal speed the governor will contract and direct the detent out of the path of the stem of the valve 26 whereupon compression will again take place in

the chamber 10 and fuel be directed into the combustion chamber.

The oil or fuel is directed from the tank 21 through the pipe 22 by means of compressing air into the tank and to accomplish this result we have employed any suitable form of pump 37, the piston 38 of the pump being operated by an eccentric 39 disposed on the cranked portion 40 of the shaft 9, the air being directed from the pump into the tank 21 through a pipe 41 which is provided at a suitable point between the pump and tank with a check valve 42 and the air is admitted into the pump through a similar check valve 43.

Disposed in the pipe 41 between the pump 37 and check valve 42 is a pop-valve 44, the object of said valve being that should the pressure in the tank 21 be greater than is necessary, as when the engine has attained a greater speed than required and the fuel is shut off from the combustion chamber, the pop-valve 42 will open and allow the air to escape therethrough. As soon, however, as the fuel is again directed into the combustion chamber and the pressure relieved from the tank through the pipe 22 the pop-valve 42 will close and the air will be again directed into the tank.

While we have shown a particular kind of 95 governor it will be understood that any desired form of governor may be employed such as will readily operate the detent or other construction to hold the valve 26 open. It will also be understood that any preferred 100 form of air compression pump may be employed to compress the air in the tank 21.

What we claim is:

1. The combination with a cylinder having a surrounding water jacket, and a compression chamber at one end of said cylinder, said cylinder being provided with an inlet port and an exhaust port extending through said jacket, a piston movable within said cylinder, a driving shaft and means for actuating the 105 piston, a governor actuated from said driving shaft, a pivotally mounted detent operatively connected with the governor, a mixing chamber, a pipe communicating with the compression chamber, a vertically disposed air tube 110 connecting said pipe with the mixing chamber, a valve fitted to a seat at the upper end of said tube, and a valve controlling the inlet pipe to the compression chamber and having a stem movable in the path of said detent. 115

2. The combination with a cylinder having a surrounding water jacket, and a compression chamber at one end of said cylinder, said cylinder being provided with an inlet port and an exhaust port extending through said jacket, a piston movable within said cylinder, a driving shaft and means for actuating the piston, a governor actuated from said driving shaft, a pivotally mounted detent operatively connected with the governor, a mixing 130

chamber, a pipe communicating with the compression chamber, a vertically disposed air tube connecting said pipe with the mixing chamber, a valve fitted to a seat at the upper end of said tube, a valve controlling the inlet pipe to the compression chamber and having a stem movable in the path of said detent, and a spring acting on said stem.

3. The combination with a cylinder having a surrounding water jacket, and a compression chamber at one end of said cylinder, said cylinder being provided with an inlet port and an exhaust port extending through said jacket, a piston movable within said cylinder, a driving shaft and means for actuating the piston, a governor actuated from said driving shaft, a pivotally mounted detent operatively connected with the governor, a mixing chamber, a pipe communicating with the compression chamber, a vertically disposed air tube connecting said pipe with the mixing chamber, a valve fitted to a seat at the upper end of said tube, a valve controlling the inlet pipe to the compression chamber and having a stem movable in the path of said detent, and a spring acting on said stem, and an adjustable nut on said stem between which and the bearing on said stem said spring is held.

4. The combination with a cylinder having a surrounding water jacket, and a compression chamber at one end of said cylinder, said cylinder being provided with an inlet port and an exhaust port extending through said jacket, a piston movable within said cylinder, a driving shaft and means for actuating the piston, a governor actuated from said driving shaft, a pivotally mounted detent operatively connected with the governor, a mixing chamber, a pipe communicating with the compression chamber, a vertically disposed air tube connecting said pipe with the mixing chamber, a valve fitted to a seat at the upper end of said tube, a valve controlling the inlet pipe to the compression chamber and having a stem movable in the path of said detent, and an air pump actuated from the driving shaft for forcing air from said compression chamber and fuel into the mixing chamber.

In testimony whereof we have signed our names to this specification in the presence of two subscribing witnesses.
